UNITED STATES PATENT OFFICE.

JOSEPH H. RIDDICK, JR., OF RICHMOND, VIRGINIA, ASSIGNOR OF ONE-HALF TO WILLIAM C. SCHMIDT, OF RICHMOND, VIRGINIA.

INK-WELL.

No. 800,491.

Specification of Letters Patent.

Patented Sept. 26, 1905.

Application filed October 24, 1904. Serial No. 229,698.

To all whom it may concern:

Be it known that I, JOSEPH H. RIDDICK, Jr., a citizen of the United States, residing at Richmond, in the county of Henrico and 5 State of Virginia, have invented certain new and useful Improvements in Ink-Wells, of which the following is a specification.

This invention relates to an improved ink-well for desk use.

10 The object of the invention is to provide a closed ink-reservoir of relatively large size in order to contain a supply of ink that will be kept from evaporation and becoming thick and muddy and obviate the necessity of frequent 15 replenishing, a pen-dip chamber for the exposure of a small quantity of ink and connected with said large reservoir, and an atmospheric inlet to maintain a balance or equilibrium of air-pressure, so as to automatically 20 keep the ink in the pen-dip chamber at a constant height.

The invention is illustrated in the accompanying drawings, in which—

25 Figure 1 is a vertical sectional elevation of the improved ink-well. Fig. 2 is a top plan view of same.

The reservoir A may be of any preferred shape and size. It is deemed preferable to make this of glass. A pen-dip chamber B 30 for the exposure of a small quantity of ink is attached to the side of the reservoir at its base and is in communication with said reservoir by the passage c. The particular shape of this pen-dip chamber is immaterial. 35 It must have a suitable opening d for the insertion of a pen-point, and when in use the ink standing in this opening is the only ink that is directly exposed to the atmosphere.

A suitable cap or cover e closes over the 40 pen-dip opening d. In the present instance this cap is attached by a hinge f to a collar or band g, which surrounds the top of the small chamber B. This hinge permits the cap to rest in the closed position or when 45 open to be turned up to a standing position against the front side of the reservoir. The cap is provided with an elastic pad e', which will fit closely down around the pen-dip opening.

50 The reservoir A has at its top a mouth h, through which the ink may be filled, and a screw-cap i is arranged to close this mouth air-tight. The cap has a disk washer j, of

elastic material, which insures an air-tight closure. An air-inlet passage-tube k opens 55 through the top of the reservoir and extends therefrom downward, and its lower end k' opens within the reservoir on a level with the top of said pen-dip opening d in the small chamber. The inner caliber or capacity of 60 the tube k should be large enough to prevent being easily stopped by any incrustation of ink; but the opening k² at the upper end of the tube is very small, only that of a pin-point, while the opening at the lower end is 65 relatively larger, being the size of the full caliber of the tube. This difference in the size of the two openings of the tube, the upper one being smaller, prevents any agitation 70 of the ink in the reservoir when moving or handling the ink-well. If the tube becomes incrusted, it can be removed for cleaning and then restored to position. The construction whereby this air-inlet passage or tube is attached to the reservoir A is immaterial. 75 In the present instance its upper end is tightly fixed in a disk or plug l, of suitable material, such as vulcanized rubber. The small opening k² in the tube is exposed at the upper side of the said plug. The disk or 80 plug fits in and tightly closes a hole m in the top of the reservoir, and the tube hangs pendent therefrom down inside the reservoir, and its lower open end k' is normally sealed by ink.

85 The horizontal broken line n across the reservoir A near its top indicates, for the purpose of explanation, the height or level of the ink contained in the reservoir. The space o above this level of the ink of course 90 contains air; but there is no direct atmospheric pressure in this space. As the upper end of the tube k is open to the exterior air, atmospheric pressure is present within the tube, and at its lower end there is an air-pressure which is in balance with the air-pressure at the same level of the pen-dip 95 opening d. This balance or equilibrium of pressure maintains a constant level of a small quantity of ink at the said exposed 100 opening d. When ink is removed from this opening by the pen, this level is momentarily destroyed or disturbed, and sufficient air will thereupon enter the tube k and discharge from its lower end into the ink-reservoir A 105 and thence rise in a bubble at the top space

o, and the ink will be automatically restored in the opening *d*.

While this device is especially applicable for use as an ink-well, it is to be understood 5 that it may be used for any other purpose for which its organization may be adapted.

Having thus fully described my invention, what I claim as new, and desire to secure by Letters Patent, is—

- 10 1. The combination of a liquid-reservoir; a chamber much smaller than said reservoir and at the side and base of the reservoir and in communication with the latter and said small side chamber having a top opening exposed to the atmosphere; the liquid-reservoir having an air-inlet passage whose upper end opens to the atmosphere through the top of said reservoir and from said top extends downward of uniform size within the 15 reservoir and having at its lower end an opening of same size as the cross-sectional area of the passage and terminating on a 20

level with the said small chamber-opening exposed to the atmosphere.

2. An ink-well having in combination a 25 liquid-reservoir, A; a pen-dip chamber, B, at the side and base of the said reservoir with its bottom in communication with the latter by a passage and having a top opening exposed to the atmosphere; a removable air-inlet tube, *k*, secured to the top of the reservoir and depending downward within the reservoir with its lower end fully open on a level with the atmospheric opening of said pen-dip chamber and having at its upper 30 35 end an opening to the atmosphere which opening is relatively smaller than said lower end opening.

In testimony whereof I affix my signature in presence of two witnesses.

JOSEPH H. RIDDICK, JR.
